UNITED STATES PATENT OFFICE

157,226

TABLE

Caryl F. Williams, La Canada, Calif., assignor to Brown-Jordan Co., Pasadena, Calif., a partnership composed of Robert E. Brown and Hubert W. Jordan

Application May 7, 1948, Serial No. 146,217

Term of patent 14 years

(Cl. D33—14)

To all whom it may concern:

Be it known that I, Caryl F. Williams, a citizen of the United States, residing at La Canada, in the county of Los Angeles and State of California, have invented a new, original, and ornamental Design for a Table, of which the following is a specification, reference being had to the accompanying drawing, forming part thereof, in which:

Fig. 1 is a perspective view of a table, showing my new design;

Fig. 2 is an end view thereof;

Fig. 3 is a fragmentary plan view taken as indicated by the arrows 3—3 of Fig. 1;

Fig. 4 is a fragmentary plan view taken as indicated by the arrows 4—4 of Fig. 1;

Fig. 5 is a sectional view taken along the broken line connecting the arrows 5—5 of Fig. 3; and,

Fig. 6 is a sectional view taken along the broken line connecting the arrows 6—6 of Fig. 2.

I claim:

The ornamental design for a table, substantially as shown.

CARYL F. WILLIAMS.
